METHOD OF MAKING RAZOR BLADE PACKAGES

Ross Nadeau, Newark, and Anton Rothschild, Irvington, N. J., assignors to Club Razor & Blade Manufacturing Corp., Newark, N. J., a corporation of New Jersey

Application August 15, 1940, Serial No. 352,706

7 Claims. (Cl. 93—2)

This invention relates generally to razor blades. More particularly our invention relates to an improved razor blade package and to a novel method and means for making the same.

One of the objects of our invention is to provide an improved process and apparatus for wrapping razor blades of the character described which shall consist of such steps and which shall comprise apparatus so constructed and arranged that the speed with which the blades may be wrapped or packaged shall be greatly increased thereby lowering the manufacturing cost.

Another object of our invention is to provide in a method and means for wrapping razor blades of the character described, an improved method and arrangement of apparatus whereby the wrapping or packaging of such blades may be accomplished by a continuous non-stop process.

Still another object of our invention is to provide an apparatus for wrapping razor blades of the character described which shall be characterized by certain novel constructional features relating to the blanking, blade feeding, folding and other features representing a general improvement in the art and which will, at the same time, speed up the quantity of razor blades wrapped.

A further object of our invention is to provide a highly improved razor blade package which shall be so designed that the blade contained therein will be prevented from movement with respect to the wrapper and thus the tendency for the cutting edges of the blade to break through the wrapping will be reduced to a minimum.

Further objects of our invention will become apparent in the following detailed description thereof.

In the accompanying drawings,

Fig. 1 is a schematic drawing illustrating the various steps employed in our novel process for wrapping razor blades;

Fig. 2 is an enlarged plan view of a portion of the paper strip shown in Fig. 1 and illustrating the same after the printing and blanking operations have taken place;

Figs. 3, 4, and 5 are enlarged perspective views of portions of the wrapping strip shown in Fig. 1, but illustrating further steps in our improved process;

Fig. 6 is an enlarged cross-sectional view taken substantially on the line 6—6 of Fig. 5;

Fig. 7 is a perspective view similar to Figs. 3 to 5, but illustrating a further step in our improved process;

Fig. 8 is an enlarged cross-sectional view taken substantially on the line 8—8 of Fig. 7;

Fig. 9 is a view similar to Fig. 2 but illustrating a modified form of our invention;

Fig. 10 is a cross-sectional view similar to Fig. 8 but relating to the form of invention shown in Fig. 9;

Figs. 11 and 12 are vertical sectional views through the apparatus representing an embodiment of our invention and illustrating the improved continuous wrapping process from the blanking operation of the paper web through to the insertion of the individually wrapped blades into cartons;

Fig. 13 is a slightly enlarged cross-sectional view taken substantially on the line 13—13 of Fig. 11;

Figs. 14 and 15 are enlarged cross-sectional views taken substantially on the lines 14—14 and 15—15 of Fig. 11;

Fig. 16 is an enlarged view of a portion of the blade feeding apparatus shown in Fig. 11;

Fig. 17 is a cross-sectional view taken substantially on the line 17—17 of Fig. 16;

Fig. 18 is an enlarged cross-sectional view taken substantially on the line 18—18 of Fig. 11;

Fig. 19 is an enlarged cross-sectional view illustrating in greater detail a portion of the apparatus shown in Fig. 11;

Fig. 20 is a cross-sectional view of reduced size taken substantially on the line 20—20 of Fig. 19;

Fig. 21 is an enlarged cross-sectional view taken substantially on the line 21—21 of Fig. 11;

Fig. 22 is an enlarged cross-sectional view of a portion of the apparatus shown in Fig. 21;

Fig. 23 is a cross-sectional view taken substantially on the line 23—23 of Fig. 22;

Fig. 24 is a cross-sectional view taken substantially on the line 24—24 of Fig. 22;

Fig. 25 is an enlarged cross-sectional view taken substantially on the line 25—25 of Fig. 12;

Fig. 26 is an enlarged elevational view, partly sectional, similar to a portion of the apparatus shown in Fig. 11, but illustrating a modified form of our invention; and

Fig. 27 is an end elevational view (partly sectional) thereof.

Referring now in detail to the drawings and in particular to Figs. 1 to 8 there is illustrated the various steps in our improved process for wrapping safety razor blades of the double-edged type. Heretofore the packing of razor blades of the class described has generally been accomplished in a rotary system comprising a number of stations and in which certain operations were

performed at each station. In this system a stopping of the operation of the process occurred during the time when the articles were transferred from one station to another. This intermittent operation resulted in a loss of efficiency in production. In accordance with our invention there is provided a process which is continuous and uninterrupted and by means of which we have been able to greatly increase the number of razor blades wrapped per minute.

As shown in Figs. 1 to 8 the continuous process for wrapping razor blades in accordance with our invention comprises the following steps. A strip or continuous web 30 of suitable razor blade wrapping material, such as paper, is unrolled from a reel 31 and after passing over a suitable tension roller 32 is fed through a suitable printing mechanism 33 where it is printed in accordance with a predetermined design. After the strip 30 emerges from the printing mechanism 33 it is next blanked while continuing to move in an axial direction to provide cut-out or notched areas 35 as shown in Figs. 1 and 2. Simultaneously with the blanking operation the strip 30 may be provided with score lines 36 disposed transversely of the length of the strip and suitably positioned with respect to a subsequent folding operation. A spot of glue 37 or other suitable adhesive substance is next deposited on the moving strip 30 in a predetermined position. The strip 30 continues to move on to the next station where a pair of score lines 39, parallel to the longitudinal edges of the strip 30 are provided, the strip 30, then appearing as shown in Fig. 3 where it is noted that a pair of end flaps 41 are thus formed.

While the strip 30 still continues to move axially a naked blade 40 ready for use is deposited on the said strip 30. As shown in Fig. 4 the blade 40 is disposed transversely of the length of the strip 30 and in the rectangular space formed by the pairs of score lines 36 and 39. It is noted that in accordance with our invention, the score lines 36 are spaced apart so as to leave a slight margin between each score line 36 and a cutting edge 40a of the blade 40, while the end edges 40b of the blade 40 are disposed substantially flush with the score lines 39, the purpose of this latter arrangement will soon become apparent. As the strip 30 continues to move the short flaps 41 defined by the score lines 39 and the longitudinal edges of the strip 30 are folded over from the dotted line position shown in Fig. 5 to the full line position. Due to the fact that the end edges 40b of the blade 40 substantially coincide with the score lines 39, the folding of the flaps 41 is effected with the said edges 40b as folding gauges. As clearly shown in Fig. 6 and as described above the blade 40 will thus be prevented from movement in a direction across the width of the strip 30 and will consequently remain in a fixed position, thus preventing the sharp edges 40a of the blade 40 from cutting into the paper strip 30.

The next step in the process of our invention is to cut the strip 30 at predetermined intervals on predetermined transverse cutting lines 42 to provide a pair of long flaps 43 and 44 defined by the score lines 36. The flaps 43 and 44 are then folded inwardly toward each other on the score lines 36, to overlap as shown in Figs. 7 and 8. Since the flap 44 carries the adhesive spot 37, the flap 43 is folded over first and the flap 44 caused to overlie the flap 43. A slight pressure is then exerted on the uppermost flap 44,

which causes the spot 37 to adhere to the flap 43, thus completely enveloping the blade 40 in a wrapping.

The strip 30 may be made of any suitable paper for wrapping blades, such as for example, paper having a waterproofed or waxed coating to protect the blades from corrosion due to moisture.

If desired a double wrapper may be provided 10 for the blade 40. In such case, as shown in Fig. 9 the outer wrapper may be composed of any desired material known to the art such as the strip 30 which may be printed on one side, while the inner wrapper may be waxed and may be 15 made from a second web or strip 45 overlying the strip 30', the said strips 45 and 30' being moved axially in a continuous process as hereinbefore described. In this latter form of my invention, however, a hole 46 may be provided in the strip 20 45 at predetermined intervals so that the glue spot 37 will penetrate to the outer wrapper 30' to maintain the package in closed position as shown in Fig. 10.

In accordance with our invention the continuous process above described continues with the 25 stacking of a measured number of wrapped blades, in this case five, as shown by the stack 47 in Fig. 1, after which the stack is automatically inserted in a cardboard carton 48 of customary construction and is then carried off, as 30 shown by the arrow 49, for boxing and shipping.

It is noted that by feeding the naked blades 40 on to the moving strip 30 in a transverse direction with respect to the length of the strip 30, the interval between the depositing of the blades 35 may be made much shorter than when the blades are deposited in direction with their longitudinal axes parallel to the longitudinal axis of the strip 30. Our continuous process is thereby greatly 40 speeded up by feeding the blades in a transverse direction.

In Figs. 11 to 25 there is illustrated in greater detail than that shown in Fig. 1, an apparatus for carrying out the above described process and 45 for producing, as a new article of manufacture, the wrapped blade or blade package shown in Figs. 7 and 8, which has produced satisfactory results and which also contemplates the following novel features of construction.

Any suitable type of printing mechanism well known to the art may be employed for printing the strip 30 used for wrapping the blades 40. From the printing mechanism the strip 30 is fed to a blanking device 50 shown in Fig. 11, the said 55 blanking device being so designed as to cut-out predetermined portions 35 of the strip 30 for forming the flaps 41 as hereinbefore described, without interrupting the continuous axial movement of the said strip 30. The blanking device 60 50 may comprise a pair of tension rollers 51 and 52 mounted on the shafts 53 and 54 respectively, the said shafts 53 and 54 being in turn journaled in a frame 55, as shown in Figs. 11 and 13. The upper roller 51 is mounted on an arm 56 which in 65 turn is pivotally mounted on the frame 55 by means of the pivot 57. A spring 58 supplies the tension for the roller 51.

An upper negative die 60 and a lower positive die 61 are provided, the said dies 60 and 61 being 70 so arranged that when they come together in the position shown in Fig. 13 they will blank or cut out portions 62 (see Fig. 13) forming the notches 35 shown in Fig. 2. A suitable chute A may be provided for carrying off the blanked portions 62. The following means are provided for mov-

ing the dies 60 and 61 toward and away from each other in proper synchronism with the movement of the strip 30 to render the blanking operation continuous and uninterrupted.

The die 60 is mounted on a collar 63 which is in turn freely mounted on a shaft 64. Similarly the die 61 is mounted on a collar 65 which is in turn freely mounted on a shaft 66. The shafts 64 and 66 may be integral with and at the same time eccentric with respect to the axes of a pair of shafts 67 and 68 respectively, journaled in the frame 55. It is thus seen from the above description that when the shafts 67 and 68 are rotated the shafts 64 and 66 will travel in an orbit with respect to the axes of the said shafts 67 and 68. The shafts 67 and 68 are caused to rotate by means of a main driving shaft 70, through a bevel gear 71 fixed to the said shaft 70 which is in mesh with a second bevel gear 72 fixed to a shaft 73 for rotation therewith. The shaft 73 is journaled in the frame 55. Also fixed to the shaft 73 for rotation therewith is a main driving gear 74. Directly in mesh with the gear 74 is a gear 75 fixed to the shaft 67 and an idler gear 76 mounted on a shaft 77 supported by the frame 55. A gear 78 fixed to the shaft 68 is directly in mesh with the idler gear 76.

It is therefore seen from the above described construction that when the main driving shaft 70 is rotated in a clockwise direction (as viewed from Fig. 11) the gear 74 will cause the gears 75 and 76 to rotate in a counterclockwise direction, and the gear 78 will then be rotated in a clockwise direction. The gears 75 and 78 will then be rotated in opposite directions and the dies 60 and 61, during a predetermined period of movement in their orbit will move in the same direction and at the same rate as the strip 30.

The dies 60 and 61 may be guided in their movements and prevented from lateral displacement by a pair of brackets 79 and 80 respectively slidably mounted on the rods 81.

The dies 60 and 61 may be so designed as to provide the transverse score lines 36 (see Fig. 3) simultaneously with the blanking operation.

The heretofore described automatic intermittent depositing of the adhesive 37 may be accomplished by providing an adhesive reservoir 82 (see Fig. 11) which may be fixed to the brackets 79 for movement therewith. An open tubular dispensing spout 83 is provided depending from the bottom of the reservoir 82 through which a quantity of adhesive is drawn out and deposited on the moving strip 30 each time that the spout 83 contactively engages the said strip 30 by the downward movement of the upper die 60 from its position shown in Fig. 11.

As also shown in Fig. 11, the strip 30 passes between pairs of suitably constructed tension rollers 84, 85 and 86, 87, to maintain the said strip under proper tension for the purpose of depositing a naked blade on the moving strip and of folding the end flaps 41. One suitable type of tension roller construction is shown in Fig. 14, where it is noted that in order to avoid the destruction of the adhesive spot 31, the upper rollers 84 and 86 may each be provided with a central circumferential groove 88 (see Fig. 14) of sufficient width and depth to clear the spot 31. The roller 84 is preferably provided with a pair of scoring blades 89 which automatically make the score lines 39 while the strip passes through the rollers 84, 85.

After passing through the rollers 84, 85, the strip 30 continues its axial movement to a station

where a single blade 40 is deposited thereon in the space formed by the pairs of score lines 36 and 38 by the following means.

Referring to Figs. 11 and 15 to 17 it is noted that a supply S of blades 40 in condition to be wrapped is stacked between a pair of suitable guides 90. The ends of the lowermost blade are adapted to rest upon a pair of shoulders 91. At predetermined intervals and in synchronism with the movement of the strip 30 a slidably mounted pusher member 92 is actuated so as to engage the shoulders 40c of the lowermost blade only and to dislodge the said blade from the stack S and push the same from its dotted line position shown in Fig. 17 to the full line position where it clears the shoulders 91 and is then in position to drop down to be deposited on the surface of the moving strip 30.

In order to guide the blade, which has been pushed from underneath the stack S, into its proper position on to the strip 30, there is provided a pair of fingers 93 which are designed to enter the openings 95 of the type generally provided in double-edged blades, such as the blades 40 and to move, for a predetermined interval of time, in the direction of and with the same speed as that of the moving strip 30.

The following mechanism, shown in Figs. 15 and 16 is employed for effecting the synchronized movement of the fingers 93 to insure that the blade 40 will fall into its proper position on the moving strip.

The fingers 93 are provided with integral angular extensions 93a which are in turn supported in a holding member 94 mounted on a shank 95. The said shank 95 is in turn rotatably mounted in a bearing 96 which forms a part of a vertically disposed plate 97. The plate 97, at its lower end, is fixed to a disc 98 eccentrically mounted on a shaft 99, for rotation therewith, the said shaft being in turn journaled in a bearing 100 fixed to a bracket 101. Fixed to the shaft 99 for rotation therewith is a bevel gear 102 which is in mesh with another bevel gear 103 fixed to the main driving shaft 70.

It is thus seen from the above description that when the shaft 70 is rotated, the shaft 99 will rotate to cause the plate 97 and the member 94 to move in an orbit in accordance with the eccentric disc 98. Such orbit is so designed that the fingers 93 will enter the apertures 95 of the blade 40 just as the lowermost blade has been pushed off the stack S and the said fingers 93 will move with the blade in the same direction and with the same speed as that of the moving strip 30, to deposit the said blade 40 on the strip 30 without interrupting the continuous axial movement of the said strip 30. To more positively guide the movement of the fingers 93 I have provided the upper portion of the plate 97 with a slot 104 (see Fig. 15) in which a shaft 104a forming a part of an eccentric disc 105, similar to the eccentric disc 98, freely operates. The eccentric disc 105 forms a part of a shaft 106 journaled in the bearing 107 fixed to the bracket 101. To cause the simultaneous rotation of the shafts 99 and 106, each of the said shafts 99 and 106 is provided with gears 108 and 109 respectively fixed thereto for rotation therewith and interconnected in meshing relationship by an idler pinion 110 on a shaft 111 supported by the bracket 101.

After the blade 40 has been properly deposited on the moving strip 30, as above described, the next step in the operation of our continuous

process, namely the folding of the end flaps 41 is accomplished by the following means.

As clearly shown in Figs. 11 and 18, an automatic folding device 112 is mounted adjacent the moving strip 30 as above described, the next step in the operation of our continuous process, namely the folding of the end flaps 41 is accomplished by the following means.

As clearly shown in Figs. 11 and 18, an automatic folding device 112 is mounted adjacent the moving strip 30, designed to automatically fold the end flaps 41 inwardly toward each other on the score lines 39. The said device comprises a channel-shaped member consisting of the cammed side walls 114 and a bottom wall member 115.

The width of the channel formed between the walls 114 is only slightly greater than the longest dimension of the blade 40 between ends 40b, so that the flaps 41 which have been slightly bent upwardly due to the score lines 39 will be automatically folded over flush up against the said ends 40b, using the said ends as a folding gauge. The walls 114 are disposed directly in the path of the flaps 41 of the moving strip 30, so that the folding will automatically take place, the said score lines 39 being adapted to facilitate the folding process. It is noted that the angularity of the inner surfaces of the walls 114 becomes more acute as the flaps pass through the device so that the folding process is gradual and continuous. After emergence from the folding device 112 the folded flaps 41 are pressed down by the rollers 86 and 87 through which the strip 30 passes.

The next step in our process is the cutting of the moving strip 30 on the lines 42 (see Fig. 7) to form the longer flaps 43 and 44 which may then be automatically folded over to completely envelop the blade 40 in a wrapping. For this purpose I provide the following mechanism.

A cutting blade 120 is mounted for vertical reciprocatable movement in any suitable manner customarily employed for cutting moving strips, the said blade 120 being adapted to cooperate with a shearing edge 121 of a platform 122 over which the strip 30 passes, as shown in Fig. 19.

The strip 30 is transversely cut by the blade 120 on the lines 42 to free the flaps 43 and 44 which are then folded. Immediately after the cutting operation a presser foot 150 is lowered in proper synchronized time and presses the blade and adjacent strip portion lying underneath the blade into a recess 123 which causes the long flaps 43 and 44 to bend up angularly, as shown by the dotted lines in Fig. 19. When this has been done the direction of movement of the cut strip changes as shown in Fig. 1 so that it moves in the direction of the arrow 125 and out of the path of the moving strip 30 (see Figs. 1 and 22). As shown in Figs. 21 to 24, during the time that the cut strip portions and the blade move in the direction of the arrow 125, they are caused to pass through an automatic folding device 130 similar to the folding device 112. The said folding device 130 comprises the spaced cammed walls 131 and the bottom wall member 132 forming a channel as shown in Fig. 24. The completely enveloped blade is then thrust forward to be received in a recess 133 where it is stacked as shown in Figs. 22 and 23.

As shown in Figs. 21 and 22 the presser foot 134 is so designed that it may press down on the stack in the recess 133 after each newly wrapped blade is received therein to thereby

flatten down the wrapper enveloping the blade and at the same time to cause the adhesive spot 37 to effectively hold the flaps in closed position.

The presser foot 134 may be suitably operated from the main driving shaft by the lever 200 in any suitable well known manner, such as that shown in Fig. 21. It is also noted that the presser foot 150 and the cutting blade 120 may be operated in the same manner as the operation of the presser foot 134 shown in Fig. 21, or in any other suitable manner known to the art.

After a predetermined number of blades have been stacked in the recess 133 they are automatically moved out of the recess by a pair of fingers 136 carried by a moving chain 137 connecting a pair of sprocket wheels 138 and 139 and passing over an idler sprocket wheel 201 forwardly disposed with respect to the sprocket 138. The chain 137 may be driven by a shaft 203 which in turn drives a second pair of sprocket wheels 141 (see Fig. 12) and 142 (see Fig. 21) interconnected by the conveyor chain 143. The sprocket 142 is on the same shaft 140 as the sprocket 138. The stack of wrapped blades removed from the recess 133 is carried along by the fingers on the chain 137 for a short distance, as indicated in Fig. 1 after which a pusher device 160 moves the stack of wrapped blades in the direction of the arrow 144 back to its original line and into a carton 48 which has been released from a stack W of cartons (see Fig. 12) and automatically opened for the reception of the stack of wrapped blades in any suitable manner known to the packaging art. The finished carton 146 is then deposited in a conveyor member 147 on the chain 143 to be conveyed and dropped off to a receiving chute 148.

In Fig. 25 I have illustrated one suitable manner in which the pusher device moves the stack of wrapped blades on the chain 137 into the open carton 48. It is noted that the pusher device 160 comprises a slidably mounted member 161 provided with a hook portion 162 disposed in direct alignment with a stack X of wrapped blades. The apparatus is so designed that when the stack X' of blades engaged by the fingers 136 and carried along by the movement of the chain 137 is properly positioned with respect to the dotted line position 160' of the pusher member 160 the said pusher member is caused to be slidably moved to its full line position 160. By such action it is seen that the hook portion 162 has engaged an end of the stack X' and pushed the same along the table portion 163 and into a carton, open and in waiting position to receive the same, after which it is conveyed away by the members 147, the carton flaps being ultimately closed in any suitable manner well known in the packaging art.

Since, as above described, the axial movement of the strip 30 is continuous up to the point where it is transversely cut by the cutting blade 120, we have provided the following means for maintaining the blades 40 deposited on the strip in proper position. As clearly shown in Figs. 19 and 20, at the instant when the cutter 120 is lowered into the cutting position shown, the strip 30 being in continuous movement is apt to buckle as shown at Y. In order to prevent such buckling action of the strip 30 from causing the blade 40 to be displaced from its proper position, there is provided a pair of rollers 180 and 181 adjacent the point where the cutting takes place, and at such position that a blade 40 will be frictionally held between the said rollers while the cutting

action takes place. As soon as the knife 120 is raised from the position shown in Fig. 19, the bulge Y will flatten out and the blade 40 will then proceed on its way in proper position on the strip 30 until the said strip reaches the next cutting line, when the knife 120 is again effectively brought down to sever the strip 30. The roller 181 may be mounted on a suitable shaft 182 journaled in a fixed bracket 204, while the roller 180 may be mounted on the shaft 183 which in turn is journaled in a bracket 184 pivotally mounted on a fixed pivot 185. It is thus seen that the tension force of the roller 180 against the roller 181 is the force of gravity, or the weight of the bracket 184 and the roller 180. If desired an additional weight member 186 may be added to the bracket to provide additional tension.

The roller 180 may be provided with a circumferential groove 187 to clear the adhesive spot 37. A pair of gears 188 and 189 on the shafts 183 and 182 respectively may cause the simultaneous rotation of the rollers 180, 181, the said gears 188 and 189 being driven from a driving gear 190 fixed to the shaft 183.

While in the foregoing we have described our apparatus as applied to the enveloping of the naked blades in a single wrapper, it is understood that my invention may be equally satisfactorily applied to the wrapping of blades with a plurality of wrappers. In the latter event however, to more efficiently maintain the wrapper in closed position I provide the following means for automatically punching a hole in the inner wrapper, so that the adhesive spot 37 may pass therethrough and cause the folded flaps of the outer wrappers to adhere. A blade with an inner layer 205 and an outer layer 30' formed from the strip 30, wrapped in accordance with our invention and having the holes 206 in the inner wrapper 205 is shown in Fig. 10.

As shown in Figs. 26 and 27, the eccentric operative movement of the upper and lower blanking dies 60 and 61 are utilized for automatically punching the holes 206 in the inner wrapping 205.

The inner wrapping strip 205 may be fed from a suitable source of supply (not shown) over a roller 207 after which it is passed over a second roller 208 and then fed between the rollers 51 and 52 to overlie the strip 30' and to be axially moved simultaneously therewith.

Adjustably mounted on a bracket 209, supported on the rod 81, is a positive hole punching die 210 of proper size to provide the holes 206. The die 210 is disposed on the upper side of the strip 205. Disposed on the opposite side of the strip 205 from that of the die 210 is a cooperating negative hole punching die 211. The die 211 is mounted on the bracket 79, for integral movement with the blanking die member 60, so that each time the blanking die 60 moves from the down position shown in Fig. 26 to the up position shown in Fig. 11, the dies 210 and 211 will have been brought together to punch a hole 206 in the strip 205. A chute portion 212 (see Fig. 27) may be provided to carry away the punched out portions of the strip 205. The operation of the above mentioned hole punching device is so synchronized with respect to the movement of the upper blanking die 60, and consequently with the movement of the reservoir 82 that the spot of adhesive 37 will be deposited through the opening 206 and on the strip 30'. It is thus seen from the above description that when the double wrapper package is manufactured the

spot of adhesive 37 will hold the enveloped blade 40 in wrapped condition in the manner clearly shown in Fig. 10 of the drawings.

It is therefore seen that by our invention we have produced an improved blade package in which the blade contained therein will be prevented from shifting within the wrapping and thus the tendency of the sharpened edges of the blade to cut through the package is eliminated. 10 Also by our inventive process the wrapping of razor blades may be greatly speeded up, and at the same time simplified.

While in the drawings we have shown one suitable apparatus for producing the wrapped blade 15 of our invention and for practicing our process, it is understood that other suitable blade wrapping and packaging apparatus known to the art may be satisfactorily employed for carrying out the various steps of our process. However, particular attention is drawn to the apparatus for 20 performing the blanking and blade feeding operations as well as other portions of the apparatus which are disclosed in greater detail and contain certain novel constructional features 25 which come within the scope of the present invention.

In accordance with the provisions of the patent statutes, I have herein described the principle and operation of my invention, together 30 with the construction which I now consider to represent the best embodiment thereof, but I desire to have it understood that the construction shown is only illustrative and that the invention can be carried out by other means. Also, while 35 it is designed to use the various features and elements in the combination and relations described, some of these may be altered and others omitted without interfering with the more general results outlined, and the invention extends 40 to such use.

Having described my invention what we claim and desire to secure by Letters Patent is:

1. In a method of wrapping razor blades of the character described the steps comprising 45 moving a strip of blade wrapping material axially, blanking out opposed portions of said moving strip adjacent the longitudinal edges thereof to form pairs of end flaps, intermittently depositing razor blades on said moving strip with the longitudinal axes of said blades at right angles to the axis of said strip, scoring said end flaps to provide fold lines therefor at points coinciding with the unsharpened end edges of said blades and transversely cutting said moving 50 strip between each pair of adjacently disposed blades.

2. In a method of wrapping razor blades of the character described the steps comprising moving a strip of blade wrapping material axially, blanking out opposed portions of said moving strip adjacent the longitudinal edges thereof to form pairs of end flaps, intermittently depositing razor blades on said moving strip with the longitudinal axes of said blades at right 55 angles to the axis of said strip, scoring said end flaps to provide fold lines therefor, folding said end flaps inwardly toward each other and over one side of said blade on said scored fold lines and against the end edges of said blade, said end edges of said blade serving as folding gauges, and transversely cutting said strip between each pair of adjacently disposed blades.

3. In a method of wrapping razor blades of the character described the steps comprising 70 moving a strip of blade wrapping material axi-

ally, blanking out opposed portions of said moving strip adjacent the longitudinal edges thereof to form pairs of end flaps, intermittently depositing razor blades on said moving strip with the longitudinal axes of said blades at right angles to the axis of said strip, providing said end flaps with fold lines, automatically folding said end flaps inwardly toward each other and over one side of said blade on said fold lines and against the unsharpened end edges of said blade, and transversely cutting said strip between each pair of adjacently disposed blades.

4. In a method of wrapping razor blades of the character described the steps comprising moving a strip of blade wrapping material axially, blanking out opposed portions of said strip adjacent the longitudinal edges thereof while the said strip continues to move, to form pairs of end flaps and subsequent pairs of side flaps, scoring said end flaps while said strip continues to move to provide fold lines therefor, depositing a spot of adhesive on one of said side flaps, intermittently depositing razor blades on said strip while said strip continues to move, said blades being disposed in alignment with and between pairs of end flaps and with the longitudinal axes of said blades at right angles to the direction of motion of said moving strip, first folding said end flaps inwardly towards each other over said blade, then folding the said side flap having the adhesive spot thereover, then folding said other side flap to overlie said adhesive spot and exerting a slight pressure to cause said side flaps to be joined by said adhesive.

5. In a method of wrapping razor blades of the character described the steps comprising continuously moving a strip of blade wrapping material in a given direction, blanking out opposed portions of said strip adjacent the longitudinal edges thereof while the said strip continues to move, to form pairs of end flaps and subsequent pairs of side flaps, scoring said end flaps while said strip continues to move to provide fold lines therefor, intermittently depositing razor blades on said strip, while said strip continues to move, said blades being disposed in alignment with and between pairs of end flaps and with the longitudinal axes of said blades at right angles to the direction of motion of said moving strip and automatically causing said end flaps to be folded inwardly toward each other

on said scored fold lines and against the end edges of said blades, while said strip continues to move.

6. In a method of wrapping razor blades of the character described the steps comprising causing a strip of blade wrapping material to be moved in a given direction, blanking out opposed portions of said strip adjacent the longitudinal edges thereof while the said strip continues to move, to form pairs of end flaps and pairs of side flaps, scoring said end flaps while said strip continues to move to provide fold lines therefor, intermittently depositing razor blades on said strip while said strip continues to move, said blades being disposed in alignment with and between pairs of end flaps and with the longitudinal axes of said blades at right angles to the direction of motion of said moving strip, automatically folding said end flaps inwardly toward each other on said scored fold lines and against the end edges of said blades while said strip continues to move and transversely cutting said strip between each adjacent pair of blades on a predetermined cutting line, while said strip continues to move.
7. In a method of wrapping razor blades of the character described the steps comprising moving a strip of blade wrapping material in a given direction, blanking out opposed portions of said strip adjacent the longitudinal edges thereof while the said strip continues to move, to form pairs of end flaps and pairs of side flaps, scoring said end flaps while said strip continues to move to provide fold lines therefor, intermittently depositing razor blades on said strip while said strip continues to move, said blades being disposed in alignment with and between pairs of end flaps and with the longitudinal axes of said blades at right angles to the direction of motion of said moving strip, automatically folding said end flaps inwardly toward each other on said scored fold lines and against the end edges of said blades while said strip continues to move, transversely cutting said strip between each adjacent pair of blades on a predetermined cutting line while said strip continues to move and folding said side flaps inwardly toward each other to overlap and completely envelop each individual blade.
